UNITED STATES PATENT OFFICE

LEO M. HARVEY, OF LOS ANGELES, CALIFORNIA

TIE FOR METAL STRAPS

Application filed October 2, 1929. Serial No. 396,848.

The principal object of my invention is to provide a tie for metal straps in which metal straps of flat and substantially wide cross section after having been drawn tightly around a box may be attached together at their ends in such a manner that a strong joint or tie is provided which will not ordinarily pull apart under conditions of use.

A more specific object of my invention is to provide a tie for metal straps in which the ends of the strap are substantially overlapped and the overlapping portions of the strap are rolled transversely into substantially round cross section and crimped transversely of the roll. I prefer to crimp the roll of the two overlapping sections of strap in such a manner that alternating annular or semi-annular ribs and grooves are formed transversely of the rolled strap portions, and particularly so that the cross section of the rolled strap portions will be compact and interlocked so as to prevent the severing of the joint or tie.

It is an object to provide a tie in which annular or semi-annular ribs may be formed on the periphery of the rolled strap portions in inter-locking relationship such as by providing a series of ribs and grooves on one portion of the roll, and another series of ribs and grooves on another portion of the roll which inter-lock with and are staggered with respect to the rolls on the first mentioned portion.

Other objects will appear as the description progresses.

In the accompanying drawings I have shown a form of tie for metal straps embodying my invention in which

Fig. 1 is a top plan view substantially enlarged of a metal strap with the ends thereof tied together.

Fig. 2 is a side view of the tie shown in Fig. 1.

Fig. 3 is a bottom view of the tie shown in Fig. 1.

Fig. 4 is a modified form of tie.

Fig. 5 is a transverse section of a tie as shown on line 5—5 of Fig. 1.

Fig. 6 is a view similar to Fig. 5 showing a modified form of roll.

My invention comprehends a tie such as is shown in Figs. 1 to 4 inclusive which is adapted to be formed on substantially flat metal straps 1 intermediate the ends 2 and 3 of the strap after the strap has been tensioned around a box, crate, bale, or the like. The tie 4 is formed intermediate the ends 2 and 3 and is substantially elongated but sufficiently inwardly of the ends 2 and 3 as to permit said ends, when the tie is completed to rest flatwise against the body of the band 1, as shown for instance in Fig. 2. The tie 4 is formed by rolling the intermediate portions of the overlapped ends 2 and 3 of the strap transversely, the two overlapping portions of the strap being rolled about a common axis. In the formation of the tie 4 the initial operation would consist in rolling the overlapping portions of the strap, and finally the two rolls, when compactly formed as shown in Fig. 5, are crimped transversely of the rolls so as to inter-lock and retain the rolled portions in their tied positions.

As shown in Figs. 1, 2 and 3, I may by suitable means, form the rolls 5 and 6 of the tie 4 with a series of alternating peripheral ribs 7, 7 etc., and grooves 8, 8 etc., while on the opposite side of the tie 4 I may provide a series of similar peripheral ribs 9 and grooves 10. Preferably the grooves 8 and 10 are slightly narrower than the ribs 7 and 9 so that as shown in Fig. 1 the grooves 10, for instance, may extend for a short distance into the adjacent ribs 7, thus providing portions 11, 11 etc., at the junctions of the ribs and grooves which serve to substantially reinforce the tie and prevent the ends of the strap from being severed under strain.

In the form of tie described it will be noted that the ribs and grooves on one-half of the tie are staggered with respect to the ribs and grooves on the other side of the tie.

Intermediate the extremities of the tie 4 and the ends 2 and 3 of the strap 1 I provide sufficiently lengthened portions 12 and 13 which are flared outwardly from the extremities of the tie to the ends of the strap so that the portions 12 and 13 may be gradually shaped from the rounding form of

the rolls into the flat cross section of the strap, as shown in Figs. 2 and 3.

As shown in Figs. 5 and 6, the outer edges 14 and 15 of the rolled portions of the tie 5 either substantially abut or overlap the opposite edges 16 and 17.

As a modified form of tie I may provide, as shown in Fig. 4, a series of V-shaped or triangular ribs 18, 18 etc., and grooves 19, 10 19 etc., in which arrangement the grooves 19 will inter-lock with the ribs 18. In this form of tie the ribs 18 and grooves 19 may be continuous around the periphery of the tie 4, or there may be two series of such ribs 15 and grooves to correspond to the transverse ribs and grooves of the form shown in Fig. 1.

I also conceive it possible to arrange the ribs and grooves in helical form around the ties 4, or otherwise, without departing from 20 the spirit of my invention, it being only necessary to reinforce and inter-lock the rolled portions of the tie so that they will withstand the tension and strain of usage.

What I claim is:

- 25 1. A tie for connecting the overlapping ends of a metal strap comprising two rolls of metal formed on a common axis and extending longitudinally of the strap but intermediate the ends thereof, the end portions 30 of the strap being flat and engaging the flat body of the strap, and the portions intermediate the ends of the strap and the extremities of the tie being gradually flared outwardly as described.
- 35 2. A tie for connecting the overlapping ends of a metal strap comprising two rolls of metal formed on a common axis and extending longitudinally of the strap but intermediate the ends thereof, the end portions 40 of the strap being flat and engaging the flat body of the strap, and the portions intermediate the ends of the strap and the extremities of the tie being gradually flared outwardly as described, the peripheries of 45 said rolls being correspondingly crimped transversely of the rolls to provide interlocking peripheral portions so as to prevent longitudinal movement of one end of the strap with respect to the other.
- 50 3. A tie for connecting the overlapping ends of a metal strap comprising two rolls formed on a common axis and provided with transversely inter-locking crimps on the peripheries thereof for preventing the relative longitudinal movement of said rolls.

4. A tie for connecting the overlapping ends of a metal strap comprising two rolls substantially overlapped at their opposite 55 edges of circular cross section and formed on a common axis, and a plurality of alternating ribs and grooves formed transversely on the peripheries of said rolls, the ribs and grooves of one roll inter-locking with the 65 ribs and grooves of the other roll for pre-

venting the relative longitudinal movement of the roll.

5. A tie for connecting the overlapped ends of a metal strap consisting of two rolls formed on a common axis with the opposite 70 edges substantially overlapped, opposite portions of the peripheries of said rolls being formed with alternate ribs and grooves transversely of the rolls, the ribs and grooves on one portion of the rolls being staggered 75 with respect to the ribs and grooves on the other portion of the roll, the grooves of one of the series at the junction of the two series of the ribs and grooves projecting into the ribs of the adjacent series for reinforcing 80 the tie.
